PLASTER GROUND

Harry Grimes, Evergreen Park, Ill.

Application July 21, 1934, Serial No. 736,380

7 Claims. (Cl. 72—101)

This invention relates to plaster grounds and more particularly to supporting means therefor.

One of the objects of the invention is to provide means for supporting a plaster ground which is simple in construction and economical in installation.

Another object is to provide means for attaching a plaster ground to walls of various formation, such as metal lath, tile or the like. This means comprises a bracket having flexible arms adapted to be clamped to the plaster ground. Another object is to provide a U shaped connecting member mounted on a wall and adapted to support a flexible U shaped bracket.

When it is desired to install the device upon a tile wall or the like, aligned perforations may be formed along the wall. Connectors, comprising U shaped members are adapted to have one leg thereof driven through the perforations. The arrangement is such that when the connector is driven home the bracket carried thereby will be clamped to the wall. The plaster ground may then be mounted between the arms of the bracket adjacent the wall, and clamped thereto by bending the outer ends of the bracket arms adjacent the outer face of the plaster ground. Where a metal lath is used, the U shaped connector is eliminated and one arm of the bracket prolonged to provide a finger grip. The shorter arm may be inserted through the lath, around the usual skeleton supporting frame for the lath and outwardly through the lath again with the bight portion thereof adjacent the frame in an upright position.

With these and other objects in view, the invention will be better understood by reference to the following specification and accompanying drawing wherein like characters represent corresponding parts and wherein:

Fig. 1 is a perspective view of the invention as applied to a tile wall with parts broken away.

Fig. 2 is an enlarged section taken along the line 2—2 in Fig. 1.

Fig. 3 is a perspective view showing the method of assembling one of the supporting units.

Fig. 4 is an elevational view of a portion of metal lath with one of the brackets in place with the connector eliminated.

Fig. 5 is a vertical section wherein the plaster ground is shown clamped to the metal lath and the plaster wall applied.

Fig. 6 is a perspective view of one of the brackets used with metal lath and

Fig. 7 is a further modified form wherein locking tabs are eliminated.

Fig. 8 is a further modified form of supporting unit adapted for use with a metal plaster ground.

In the drawing 1 indicates a tile wall having the usual slots 2 in the outer face 3 thereof. A flexible U shaped bracket is shown at 4 of substantially the width of the slot 2 and having arms 5 and 6. The arms 5 and 6 are provided with aligned openings 7 and 8 respectively adjacent the bight portion 9. A substantially U shaped connector is shown at 10 formed of round wire 10 having legs 11 and 12. The legs are pointed, the leg 12 being provided with an outwardly bent end 13. The connector 10 is adapted to be mounted in the bracket 4. The openings 7 and 8 are substantially larger in diameter than the connector 10. 10 is in cross section. As shown in Fig. 3, the leg 12 is mounted through the opening 7 at an angle with respect to the plane of the bight portion 9 and extended downwardly to the opening 8. As the leg 12 is extended the same is gradually 20 drawn in the plane of the bight portion 9 until the portion 13 is arranged beneath the arm 6. The connector 10 is then turned to the position shown in Fig. 2. The connector 10 is adapted to connect the bracket to the wall 1 and this is done 25 in the following manner. Openings 14 are punched in alignment at spaced intervals at a predetermined point on the wall 1 in certain of the slots 2. The legs 11 are then inserted in the openings and driven downwardly. As the connector 10 is driven home, the leg 12 is drawn inwardly thereby binding the bight portion 9 against the inner face 15 of the slot 2 with the arms 5 and 6 extending outwardly horizontally. A wood plaster ground 16 of rectangular cross 35 section is adapted to fit snugly between the arms 5 and 6. The arms are of greater length than the thickness of the plaster ground 16 and are adapted to be bent over against the outer face 17 thereof to form locking tabs 18 and 19, after 40 which the plaster wall 20 is applied.

In Figs. 4 and 6 inclusive, is shown a modified form of bracket adapted to support a wood plaster ground on a metal lath wall. In this form 21 indicates a portion of a metal lath wall having 45 the usual skeleton frame, one portion of which is shown at 22. A flexible U shaped bracket 23 having arms 24 and 25 is adapted to be mounted on the wall 21. The arm 25 is of greater length than the arm 24 and is adapted to be gripped at 50 the outer end 26 thereof by the fingers of a worker. The end 27 is adapted to be inserted through one of the openings 28 in the lath 21 at one side of one of the uprights 29 of the frame 22 and then threaded outwardly through another of 55

the openings 28 at the other side of the upright 29 with the bight portion 30 of the bracket 23 in abutment with the inner face 31 of the upright 29. A wood plaster ground 16' is adapted to be mounted adjacent the wall 21 between the arms 24 and 25, after which the ends 27 and 26 are then bent against the outer face 17' of the plaster ground 16' to form locking tabs, after which the plaster wall 20' is applied. The brackets are formed of flexible and perforable material. In Fig. 7 the arms 5' and 6' are shown as of a length substantially equal to the thickness of the plaster ground 16, and nails 18' driven therethrough into the plaster ground. If desired perforations may be formed in the arms prior to installation of the brackets to facilitate locating and driving the nails into the plaster ground. The leg 12' is shown of a length greater than the bight portion 9' to facilitate sliding of the bracket thereon should one of the openings be misaligned. In Fig. 8 is shown a further modified form wherein the supporting units are adapted to connect a sheet metal plaster ground. In this form the bight portion 32 is perforated at 33 adjacent the inner arm 34 of the U shaped brackets 35. The connectors 10 are adapted to clamp the arm 34 against the face 15' of the slot 2' in the tile wall 1' with the bight portion 32 in a horizontal position. A U shaped metal plaster ground 36 is adapted to be mounted upon the bight portions 32 and is provided with an S shaped outer portion. The outer arm 37 of the bracket 35 is adapted to be arranged between the walls 38 and 39 of the S shaped portion, whereby to connect the plaster ground to the wall 1; after which the plaster wall 40 is applied. From the foregoing it will be seen that I have provided a simple supporting means for plaster grounds which is economical in manufacture and installation and wherein no nails are needed, the device having been installed in practical use with a great saving in cost of labor and time.

Having thus described my invention, what I claim is:

1. A device of the class described including, in combination, a wall, a staple having one leg thereof imbedded in said wall, a plaster ground, and a U shaped supporting member adapted to receive said plaster ground, said supporting member having the bight portion thereof in abutment with said wall and having aligned openings in the legs thereof, the other leg of said staple

adapted to be arranged in said openings and having a hook on the end thereof adapted to support said supporting member.

2. A device of the class described including, in combination, a wall, a staple having one leg imbedded in said wall, a plaster ground, and a flexible U shaped strip of material adapted to receive said plaster ground and having openings in the legs thereof adjacent its bight portion, the other leg of said staple adapted to be arranged in said openings and having an outwardly turned portion adapted to support said strip.

3. A device of the class described including, in combination, a wall, a staple having one leg thereof imbedded in said wall, a U-shaped supporting member having openings adapted to slidably receive the other leg of said staple, and a plaster ground adapted to be mounted in said U shaped supporting member.

4. A device of the class described including a staple having a hook formed on one leg thereof, and a U shaped supporting member having perforations therein adapted to slidably receive said leg.

5. A device of the class described including, in combination, a plaster ground, a staple having an outwardly bent portion on one leg thereof, and a U shaped flexible strip of material having aligned perforations adapted to slidably receive said leg and having opposed fingers formed on the outer ends thereof, said fingers being adapted to hold said plaster ground in position.

6. A device of the class described including, in combination, a staple having an inner and an outer leg, and a perforated U shaped flexible supporting member having an upper and a lower leg, said outer leg adapted to be mounted in the legs of said supporting member adjacent the bight portion thereof and having an outwardly turned end portion adapted to support said supporting member.

7. A device of the class described including, in combination, a staple having an inner and an outer leg, and a perforated U shaped flexible supporting member having an upper and a lower leg, said outer leg adapted to be mounted in the legs of said supporting member adjacent the bight portion thereof and having an outwardly turned end portion adapted to support said supporting member, said upper and lower legs being bent inwardly in opposed relation at their outer ends.

HARRY GRIMES.
